(57) **CLAIM**

The ornamental design for a display screen or portion thereof with graphical user interface, as shown and described.

DESCRIPTION

FIG. 1 is a front view of a display screen or portion thereof with graphical user interface showing our new design; FIG. 2 is a front view of a display screen or portion thereof with graphical user interface showing a second embodiment of our new design; and,

FIG. 3 is a front view of a display screen or portion thereof with graphical user interface showing a third embodiment of our new design.

The broken lines around the Figures show a display screen or portion thereof, and form no part of the claimed design.
